Patented Jan. 1, 1918.

UNITED STATES PATENT OFFICE.

JOHN P. SINGISER, OF ROCHESTER, NEW YORK.

AUTOMATIC VALVE.

1,252,046.

Patented Jan. 1, 1918.

Application filed February 2, 1916. Serial No. 75,856.

To all whom it may concern:

Be it known that I, JOHN P. SINGISER, a citizen of the United States, residing at Rochester, in the county of Monroe and State of New York, have invented certain new and useful Improvements in Automatic Valves, of which the following is a specification.

The object of this invention is to provide a valve in which the water pressure will automatically close the valve without jarring.

This and other objects of the invention will be fully illustrated in the drawings, described in the specification and pointed out in the claim at the end thereof.

In the drawings,

Figure 1 is a vertical section through the valve, the section being taken on the line 20 1^x—1^x of Fig. 3.

Fig. 2 is a vertical transverse section through the dash pot which governs the closing of the valve.

Fig. 3 is an end elevation of the valve 25 casing.

Fig. 4 is a top plan view of the cross head and antifriction roller.

In the accompanying drawings like reference numerals indicate like parts.

In the drawings reference numeral 1 indicates the valve casing which is divided longitudinally by a vertical partition 2, and transversely by a vertical partition 3, the vertical partition 3 being on the high pressure side of the partition 2 and separating the valve chambers for the hot and cold water from each other. On top of the valve are the two inlet openings 4 and 5, one of which is intended to supply hot water and 30 the other cold water. Below the vertical casing is the outlet opening 6 which serves as a drain for both of the valves. At one end the valve casing is closed by the heads 7 and 8 and at the other end by two other heads, one of which is shown in Fig. 1 at 9. At the left hand side in Fig. 1 the valve casing is provided with a seat 10, with which 45 engages the flange 11 on the head 8, which head has integral therewith the cylinder or dash pot 12. This head has an opening 50 therein at 13 to receive the valve stem 14. At the forward end of the head are provided the guides 15 and 16, between which is adapted to slide the cross head 17 which is 55 connected to the forward end of the valve

stem 14. A pin 18 engages with the cross head 17 and passes between the guides by which the cross head is held against turning and a set screw 19 is provided by which the cross head is fastened to the valve stem. 60

On the forward end of the cross head is a pair of lugs 20 and 21 between which is mounted an anti friction roller 22.

On the forward end of the guides 15 and 16 are provided lugs 23 and 24 between 65 which is mounted the shaft 50 on which are the handle 25 and the ratchet cam plate 26. The handle 25 carries the projection 51 that engages the cam plate and causes it to turn when the handle is lifted. The cam 70 surface 27 on this plate engages with the anti friction roller 20 and when the handle is raised from the position shown in Fig. 1, the cam will react against the roller and force it and the piston stem to the right. 75 Pivotaly mounted on top of the head 11 is the pawl 28 which is adapted to engage with the teeth of the plate 26 and hold it in any position to which it has been advanced, while the handle that has raised it is free to swing 80 back to normal position.

On the other end of the valve casing is provided the head 9 which has a threaded engagement with the valve casing and is provided with a flange 29. The head is recessed at 30 to form a guide for the end of the valve stem. Inside of the valve casing is provided a seat 31 for the valve 32, which valve is integral with the valve stem. The valve stem is also provided with a piston 33 90 that engages with the cylinder 12 and forms a dash pot therewith. This piston is provided with a small opening 34 therethrough, which opening is normally closed by the semi-circular spring 37 fastened to the piston at 38. 95

Through the head of the valve casing is provided a passage way 35 which connects the forward end of the cylinder 12 with the interior of the valve chamber. The size 100 of this opening in the passage way is controlled by the needle valve 36 mounted in the head of the valve casing and making threaded engagement therewith so that it can be screwed in or out to change the size 105 of the opening in the passage way 35.

The valve stem, where it passes through the head of the valve casing, is packed by a stuffing box 39.

The foregoing describes the construction 110

of the valve and heads of the valve casings, etc., shown at the right of Fig. 3, but it will be understood that the same description applies equally well to the corresponding parts shown or indicated on the left of Fig. 3.

The operation of my device is as follows: When the valve casing is connected up to the water supply the pressure of the water will force the valve 32 forward onto its seat and shut off the flow of water into the chamber 40. When it is desired to admit water, the handle 25 will be raised as far as it is desired causing the valve 32 and the piston 33 to move to the right. This will permit water to flow past the valve and the water will fill the cylinder 12 and exert sufficient pressure to lift the valve 37 and fill the chamber between the cylinder 12 and piston 33, it being understood that the spring 37 is very light and does not have much resistance. When it is desired to close the valve the pawl 28 will be lifted and the pressure on the valve 32 will force the valve and the valve stem 14 forward. In moving forward, however, the piston 33 must force the water that has accumulated between it and the cylinder 12 out through the passage way 35 which has been partially throttled by the needle valve 36. The water will slowly pass out through the passage way 35 and will cause the valve 32 to gradually seat itself, thus preventing it from closing suddenly and with a jar.

To provide for the simultaneous lifting of the pawls 28 I provide the yoke 41 having pins 42 thereon which engage with the

pawls 28 by which they may be simultaneously lifted.

I claim.

The combination of a valve casing, a partition therein, a valve seat on one side of said partition, a valve adapted to seat itself on said seat, a valve stem projecting from either side of said valve, guides at each end of said casing to guide said valve stem in a straight line movement, a piston on said valve stem, a cylinder having an open end and a closed end in said casing, said piston being adapted to slide in said cylinder, a by-pass connecting the closed end of said cylinder with said casing, an opening 40 through said piston, a spring pressed valve 45 on said piston, closing said opening when the piston moves in one direction, guides on the outside of said casing, a cross head 45 mounted to slide between said guides, said cross head being fastened to the end of said valve stem, an anti-friction roller mounted 50 on said cross head, bearings on the outer ends of said guides, a cam mounted between said guides, said cam being adapted to rest 55 on said anti-friction roller and open said valve on the rotation thereof, a handle mounted to rotate in said bearings and independently of said cam, said handle being 60 adapted to engage said cam and rotate said cam, a ratchet provided on the periphery of said cam, a pawl mounted on said casing, 65 said pawl being adapted to successively engage the teeth of said ratchet on the rotation of said cam.

In testimony whereof I affix my signature.

JOHN P. SINGISER.
